V. VERNEY

CENTRIFUGAL MACHINE

Filed March 4, 1924

*V. Verney Inventor
by J. J. Durie A.F.T.Y.*

UNITED STATES PATENT OFFICE.

VINCENZO VERNEY, OF ROME, ITALY.

CENTRIFUGAL MACHINE.

Application filed March 4, 1924. Serial No. 696,867.

To all whom it may concern:

Be it known that I, VINCENZO VERNEY, a subject of the King of Italy, and residing at 217 Via Emanuele Filiberto, Rome, Italy, have invented certain new and useful Improvements in Centrifugal Machines, of which the following is a specification.

This invention relates to centrifugal machines adapted to separate from liquids solid substances in suspension therein.

It has for its object to construct a centrifugal machine of this type so that the solid substances which adhere to the walls of the drum after the separating operations, may be stirred up and mixed with fresh liquid fed to the machine and be washed after the liquid from which such solid substances have been separated has been removed or discharged from the apparatus.

For this purpose, the invention consists in arranging within the centrifugal machine a stirring device adapted to bring the solid substances previously separated from the liquid, again into suspension in fresh liquid fed to the machine, this stirring device being constructed and arranged so as not to interfere with the working of the machine when it is used to separate the solid substances from the liquid.

The invention will be described with reference to the accompanying drawing which shows two embodiments of the invention, Figures 1 and 2 being respectively a sectional elevation and a plan view of the improved construction.

As shown in the drawing, a case 1 has entering it a shaft 2 to which is secured a rotary drum 3. The shaft 2 is driven so that it may rotate at a high speed when the machine is used to separate the solid substances from the liquid, and at a low speed when the substances that have been separated are being stirred up and washed.

A shaft 4 which is arranged in parallelism with the shaft 2 enters the drum and is fitted with arms 5 carrying paddles 6. These paddles extend along the walls and the bottom of the drum 3. The arms 5 and the paddles 6 are bent, their radius of curvature being equal to the distance between the shafts 4 and 2. The paddles 6 are arranged so that their front edge is apt to engage the wall of the drum in the direction of rotation of the drum, as will hereafter be explained. The shaft 4 rotates in bearings 7

and 7' which are supported from the cover of the case 1. A hand lever 8 which by means of a bolt 10 may be clamped in any desired position on a slotted arc piece 9 serves to rotate the shaft 4 carrying the paddles 6. The liquid to be treated is introduced through a pipe 11, whereas after treatment the clear liquid is discharged through a pipe 12. This pipe 12 is screw-threaded at one end and may be adjusted by aid of a hand-wheel 13 so that the radial position of the nozzle of the pipe 12 may be adjusted at will. The support of the hand-wheel 13 is connected through a rod 14 to a bearing 15 which surrounds the shaft 2, so that the pipe 12 will follow the pendular movements of the drum 3, but will not follow its rotary movements. The drum is divided into compartments by horizontally arranged perforated circular partitions 16 whose outer edge is in contact with the wall of the drum.

When the solid substances in suspension in a liquid are to be separated therefrom the device will work as follows. The liquid containing the solid substances is introduced into the drum through the pipe 11. The paddles occupy the position shown in Figure 2 and therefore do not project into the layer of liquid which will be formed adjacent the wall of the drum when same is rotating at a high speed. Owing to their curved shape the paddles do not interfere with the rotation of the drum as they cannot exert a braking action on the liquid. When the solid substances have been separated from the liquid the latter is withdrawn by aid of the pipe 12. This operation is continued until the layer of solid substances at the wall of the drum has reached a sufficient thickness.

When the layer of solid substances has reached the desired thickness the washing liquid is introduced into the drum through the pipe 11. The drum is slowed down and the paddles 6 are brought to engage the wall of the drum through the shaft 4 being turned by means of the hand lever 8. The solid substances are thus stirred up and are made to enter the liquid so as to be in suspension therein.

When the stirring operation has been finished the paddles 6 are moved back to their original position, the drum is again made to rotate at a high speed and the solid

substances are thus again separated from the liquid. Of course, the stirring and washing operation may be repeated if desired, and at the end of the operations the solid substances are stirred up in fresh liquid and the muddy mass thus obtained is discharged through an opening provided in the bottom of the drum and normally closed by a cover.

It is not necessary that the paddles should be mounted so as to be able to rotate, as described, any other suitable arrangement may be provided to prevent their entering the liquid mass at the wall of the drum during the separating operations, for example they may be displaced radially or along a straight line along a cord of the periphery of the drum.

The horizontally arranged perforated partitions 16 are intended to make the liquid follow the rotary motion of the drum. The arms carrying the paddles may be rigid or elastic and they may be fitted with one or more paddles which themselves are rigid or flexible or articulated. The lower end of the shaft 4 which will remain immersed in the liquid until the drum has reached a certain speed, is preferably of an oblong shape or reduced to a smaller diameter in order to diminish the resistance it offers to the liquid.

What I claim is:

1. A centrifugal machine, including a drum, means for rotating the drum, a paddle shaft entering the drum, a series of paddles carried by the shaft, means for manually adjusting the shaft to arrange the paddles in contact with or free of contact with the wall of the drum, and means arranged beyond the drum for fixing the shaft in adjusted position.

2. In a centrifugal machine, a rotating shaft, a drum supported thereby; a paddle shaft projecting into the drum at one side of the rotating shaft, a series of paddles carried by the paddle shaft, and means for adjusting the paddle shaft to arrange the ends of the paddles in contact with or free of contact with the drum, said paddles being curved to correspond with the curvature of the drum, whereby when the paddles are free of contact with the drum no braking action is had on the liquid by the paddles.

In testimony whereof I have signed my name at Rome this fifth day of January 1924 in the presence of two subscribing witnesses.

VINCENZO VERNEY.
